WIRE STRETCHER

Walter W. Parks, Bloomington, Ind.

Application February 3, 1947, Serial No. 726,067

7 Claims. (Cl. 254—67)

1

This invention relates to new and useful improvements and structural refinements in wire stretchers, more specifically, wire fence stretchers, and the principal object of the invention is to provide a device of the character herein described, which may be conveniently and effectively employed for stretching the wire fence preparatory to the securing thereof on the fence post.

A further object of the invention is to provide a wire stretcher which may be quickly and conveniently adjusted to facilitate operation thereof on uneven ground.

Another object of the invention is to provide a wire stretcher which is simple in construction and operation, and which may be easily manipulated.

An additional object of the invention is to provide a wire stretcher which will not easily become damaged and which is otherwise well adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is a side elevation of the invention, showing the same in use;

Figure 2 is a top plan view of the invention per se, and

Figure 3 is a perspective view of a block used in the invention.

Like characters of reference are used to designate like parts in the specification and throughout the several views.

Referring now to the accompanying drawings in detail, the invention consists of a wire stretcher designated generally by the reference character 10, the same embodying in its construction a tubular member 11, one end portion of which is telescoped in a tubular extension 12, while the remaining end of the member is bifurcated to provide a fork 13.

A suitable fastener, such as a length of chain 14, is equipped at the ends thereof with a pair of screw eyes 15, the latter in turn, being selectively receivable in transversely aligned apertures 16 formed in the parts 11 and 12, as will be clearly apparent.

The chain 14 is adapted to encircle, as it were, the fence post 17 and is removably retained in position thereon by means of the nuts 18 with which the screw eyes are provided. It will be noted that by simply positioning the screw eyes in the various of the apertures 16, the overall length of the member 11 (including the extension

2

12) may be increased or decreased accordingly.

The aforementioned fork 13 is downwardly arcuated and the arms 19 thereof are provided at their lower extremities with suitable bearing blocks 20 which, together with further bearing blocks 21, constitute what may be referred to as a pair of knuckles 22.

A pair of extension arms 23 are each secured to one of the blocks 21, each of the extension arms consisting of a pair of slidably telescoped sections 24 and 25 which are adjustably secured together by means of suitable bolts or pins 26. These pins extends transversely through the sections 23 and are selectively receivable in a plurality of apertures 27 provided in the section 25. In this manner, the overall length of each extension arm may be independently increased or decreased, as desired.

It will be noted that the extension arms 23, in effect, constitute continuations of the arms 19, and the free extremities of the extension sections 25 rest upon the ground surface 28, as will be clearly understood.

A block 29, provided with a transversely extending, screw threaded bore 30, is also equipped with a pair of journals 31. The latter extend in relatively opposite directions with respect to one another and substantially at right angles to the axis of the bore 30. The journals 31 are rotatably positioned in the knuckles 22, as is best shown in Figure 2.

A screw threaded shaft 32, provided at one end thereof with a crank handle 33, is operatively positioned in the bore 30 of the block 29, the remaining end of the shaft being equipped with a swivel box or block 34. The latter, in turn, is provided with a hook 35, and a flexible element such as a length of rope or cable 36 is connected at one end thereof to said hook. The remaining end of the cable 36 is attached in any suitable manner (as exemplified at 37) to the fence wire 38.

When the invention is placed in use, the fastener 14 is engaged with the bolt 17, the extension arms 23 are placed upon the ground, and the cable 36 is attached to the wire 38, as has already been explained. Thereupon, by simply rotating the crank handle 33, the fence will be stretched through the medium of the cable 36, preparatory to the securing thereof on the fence post, as will be clearly apparent.

The provision of the swivel 34 will, of course, facilitate rotation of the shaft 32 without twisting the cable 36 and it should be understood that the bearing blocks 20 and 21 in each of the knuckles

22 are rigidly secured together, so as to prevent the entire device from collapsing in the direction of the arrow 39.

It should be noted, that once the cable 36 has been attached or applied to the fence wire 38, by rotating the crank handle 33 the wire will be pulled toward post 17, so that the wire may be fastened thereto by nails or the like. To tighten the wire to the adjacent post (not shown), the chain 18 is disengaged with the first post and re-engaged with the second post, by adjusting section 12 relative to section 11, whereby the device may be used without disengaging the cable with the wire 38.

Finally, the longitudinal adjustment of the 15 extension arms 23 will permit the same to be independently lengthened or shortened, so as to facilitate operation of the device on uneven ground.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the 20 invention as claimed.

What I claim as my invention is:

1. A wire stretcher comprising an elongated member, a sleeve adjustably mounted on one end of said member, a flexible strap carried by said sleeve for engaging a post, an arcuate fork element at the opposite terminal of said member, extendable arms rigidly carried by the terminals of said fork, a block pivotally carried by said fork, a screw threaded rod receivably engaging said block, a flexible element carried by said rod, and means for connecting said flexible element to a fence wire.

2. A wire stretcher comprising an elongated member, a sleeve slidably mounted on one end of said member, means for holding said sleeve in a selected adjusted position relative to said member, a flexible strap carried by said sleeve for engaging a post, an arcuate fork at the opposite end of said member, extendable arms carried by the outer terminals of said fork, a block pivotally carried by said fork, a screw threaded rod receivably engaging said block, an elongated flexible element, means connecting said flexible element to said rod, and means for connecting said flexible element to a fence wire.

3. The combination of claim 2 wherein a plurality of longitudinally spaced apertures are provided on said member and said sleeve and the

means for holding said sleeve relative to said member includes fasteners selectively engaging said apertures, said fasteners having eye terminals engaging the ends of said flexible element.

4. The combination of claim 2 wherein said means connecting said flexible element to said rod includes swivel means.

5. The combination of claim 2 wherein said means connecting said flexible element to said rod includes a swivel box carried by said rod, and a hook member carried by said box for engaging one terminal of said flexible element.

6. A wire stretcher comprising an elongated tubular member, a sleeve slidably mounted on one terminal of said member, a plurality of longitudinally spaced apertures provided in said sleeve and said member, fasteners selectively engaging said apertures for holding said sleeve in selected adjusted positions relative to said member, eyes carried by said fasteners, a flexible strap removably engaging said eye for engaging a post, an arcuate fork at the opposite end of said member, extendable arms carried by the outer terminals of said fork, a block pivotally carried by said fork, 25 a screw threaded rod engageably receiving said block, hand gripping means for rotating said rod, a swivel box carried by one terminal of said rod, a hook member carried by said box, a flexible element, an eye at one end of said flexible element for engaging said hook, and means for connecting said flexible element to a fence wire.

7. A wire stretcher comprising an elongated member having an arcuate bifurcated terminal, means carried by said member for anchoring the 35 same to a fence post, extendable arms carried by the furcations of said bifurcated terminal, a block pivotally carried by said bifurcated terminal and having an internally threaded opening therein, a screw threaded rod receivably engaging the opening in said block, a flexible member having one end swiveled to said rod, and means carried by the free end of said flexible member for anchoring the same to a fence wire, said extendable arms being inclined relative to said flexible 40 member.
